Primary Examiner — Charles D Hanson*(74) Attorney, Agent, or Firm* — Edwards Lifesciences;
Linda Allyson Nassif(57) **CLAIM**

We claim the ornamental design for a stent, as shown and described.

DESCRIPTION

FIG. 1 is a perspective view of a stent;
FIG. 2 is a bottom perspective view thereof;
FIG. 3 is a front view thereof;
FIG. 4 is a left side view thereof;
FIG. 5 is a right side view thereof;
FIG. 6 is a top view thereof; and,
FIG. 7 is a bottom view thereof.

The portions of the Figures shown in broken lines are for illustrative purpose only and form no part of the claimed design.
